UNITED STATES PATENT OFFICE

EDWIN B. HUDSON, OF BUTLER, PENNSYLVANIA, ASSIGNOR TO THE AMERICAN ROLLING MILL COMPANY, OF MIDDLETOWN, OHIO, A CORPORATION OF OHIO

PICKLING TANK CONSTRUCTION

Application filed September 18, 1928. Serial No. 306,638.

In sheet mill practice the provision of pickling tanks is a serious problem, not only to provide a satisfactory acid-tight tank, but to avoid in the construction thereof prohibitive expense in the use of costly materials. The seriousness of the problem is heightened in continuous mill practice because of the much greater tank area that is required. Whereas for a spider pickler only three small tanks are used, in a continuous mill the length of tank stretches to and sometimes well beyond a hundred feet.

It is an object of my invention to provide a type of tank which may be constructed in place at a minimum of expense.

It is a further object of my invention to facilitate the use of cheaper materials in pickling tanks, and particularly re-inforced concrete.

Since some leakage and ill repair after protracted periods of use is unavoidable, still further objects of my invention are provision of means for detecting leaks and locating them within a reasonably small area, the conducting away of the leaking acid, and the protection of the concrete therefrom.

Still a further object of my invention is the provision of a novel tank construction employing hollow tiles, whereby the above objects, and others which will be apparent to one skilled in the art upon reading these specifications, will be subserved.

I attain these objects by that certain construction and arrangement of parts of which I shall now describe a preferred embodiment, reference being made to the drawings which form a part of these specifications.

In these drawings:—

Figure 1 is a view, partly in section and partly in perspective, of a portion of an acid pickling tank of my construction.

Figure 2 is a tile prepared for use on the floor of my tank.

I prepare a re-inforced concrete construction resting upon feet 1 and 2. Extending therebetween is a sub-floor 3 with a slanting upper surface. A heavy upright wall 4 rests upon the foot 1 and furnishes support for one side of the tank. The tank proper has a floor of concrete 5 and side-walls 6 and

7. The other side of the tank proper is supported upon the sub-floor by interspaced piers 8. All of this construction is preferably of re-inforced concrete (I have shown rod reinforcements at 9) and cast in one piece. It is one of the advantages of my construction that it permits the use of concrete in this fashion; but other materials may be used and will fall within the scope of my invention.

The concrete floor 5 of my tank, is of standard reinforced concrete and tile construction excepting that the tiles 10 are set in on end with the cells in a vertical position. These tiles are preferably spaced at 12" centers along the longitudinal axis of the tank. The concrete between the tiles forms girders 11, properly reinforced with steel rods to carry tension loads. These concrete girders are poured to a height of 1 inch below the top of the vertical tiles leaving a space overlying the girders. This space I fill level with a layer of asphalt mastic cement, which I have indicated at 12. Thus the floor of my tank comprises a concrete platform 5 pierced transversely by lines of acid proof hollow tile, the cells of which form conduits leading through the floor, and opening above the sub-floor 3. And the girders demarcated by these tiles are top-sealed with a coating of asphalt cement. The girders are thus protected from acid on top by the mastic and on the sides by the tiles. The tiles, as will herein-after be more fully explained, act as weep holes for any acid which may leak through the first lining.

The concrete side walls, 6, are an integral part of the floor in my preferred construction, and may be designed as a cantilever beam to resist the overturning moment of the hydrostatic head in the tank. Both walls and floor of the tank are broken at intervals to provide expansion joints which are necessary in very long tanks. I have shown one of these joints in the floor, and comprising a bent lead member 13, cast into the concrete, spanning the expansion joint opening 14, and holding in place the mastic 15. Other expansion joint constructions are, however, suitable. I find it satisfactory to provide an

expansion joint every twenty feet, more or less.

I coat the side walls with a layer 16 of asphalt mastic, making this continuous with 5 the mastic layer surmounting the floor girders. My tank is now ready for the application of the inner layers.

The floor of my tank I next lay with a course of hollow tiles 10a with the cell spaces 10 following the longitudinal axis of the tank. These tiles will be laid so that their meeting edges lie over the cell openings of the vertical tiles in the floor. Twelve inch tiles will serve for the floor providing the transverse courses 15 of vertical tiles have been laid on twelve-inch centers. The tiles 10a will have notches 10b chipped from their lower edges to permit any liquid which comes into the cells to drain therefrom into the cell openings of the vertical tiles. The corners of my tank I preferably finish with angle tile 10c. The cell partitions of these tiles are chipped away as at 20 10d to permit flow between and into the cells. There will be no notches in the bases of these 25 tiles if the transverse rows of vertical tiles stop short of the sides of the tank. Surmounting the angle tiles and covering the wall 6 is a course of tiles 10e laid with the cells vertical. When the entire tank is thus 30 lined with tiles, I coat it within with another asphalt mastic seal 17, and it is then ready to receive the acid-proof final lining.

The layer of acid proof hollow tiles, 10a, etc., serves a number of purposes. It acts as 35 insulation for the tank, which is of some importance in the use of hot pickle liquors. It makes possible the use of two mastic seals, which is a matter of great importance. The construction of a successful pickle tank involves 40 the coordination of a number of factors. The inner acid-proof lining with its mastic seal, however well protected by expansion joints and the like, is subject to cracking and leakage. A mastic seal is intended 45 to protect the non-acid-proof tank proper from corrosion under these conditions; but its action is not perfect. In my construction, I provide the tank proper with a second mastic seal separated from the first 50 by an open-work structure so that in itself it is less subject to the immediate influences tending to crack the acid-proof-lining. Again the tile cells provide weep holes or drainage openings through which pickle liquor leaking through the acid-proof lining and first mastic seal may be conducted away 55 before it can act upon the second mastic seal. The second mastic seal is therefore subject to no hydrostatic head. Acid seeping through a crack in a side wall will drip downward through the vertical channels of the tiles 10e and through the notches of the tiles 10c and 10a, until it flows out through the cells of the vertical tiles 10 in the floor, 60 and onto the sub-floor 3. The location of a

leak can be determined within a small space by observing the drip. This subfloor, I prefer to provide with an acid-proof lining 17 similar to that next to be described for the tank, and to line the interior portion of the 70 upright 4 therewith also, as at 17a. The piers 8 are made of, or lined with acid-proof material. The slantwise disposition of the top of the sub-floor causes seepage to drain into a gutter 18 by means of which it is conducted away. 75

A number of acid proof substances or constructions will serve for the acid proof lining 17b of the interior of the tank, and the linings 17 and 17a of the sub-floor and wall. 80 The one I prefer to use comprises a course of acid-proof brick laid in acid-proof cement. A satisfactory cement is a heat plastic comprising sulphur and sand; but others are suitable. At intervals along the interior lining I provide for expansion joints which preferably coincide with the expansion joints of the tank proper. A convenient form is a wooden strip 19 embedded as shown in a space left in the lining. These joints not 85 only allow for expansion and contraction, but when constructed as shown, further minimize cracking by causing the composite tank to act as a unitary construction.

The tank walls may be surmounted, as 90 shown, by granite slabs 20.

Modifications in my construction for different types of tanks will suggest themselves to one skilled in the art, as will substitution of materials.

Such changes, however, are included within the scope of my invention of which I have described a preferred embodiment; and what I claim as new and desire to secure by Letters Patent, is:

1. In a tank construction, an open cellular structure having a mastic seal on both sides thereof whereby a hydrostatic head within the tank is prevented from acting upon the outermost seal layer.

2. In a tank construction an outer wall with an inner mastic seal, and an inner wall with an outer mastic seal, said seals separated by an open cellular construction.

3. In a tank construction an outer wall with an inner mastic seal, and an inner wall with an outer mastic seal, said seals separated by an open cellular construction, comprising hollow tiles.

4. In a tank construction an outer wall with an inner mastic seal, and an inner wall with an outer mastic seal, said seals separated by an open cellular construction, comprising hollow tiles, so disposed as to provide channels to conduct away seepage coming through said inner wall.

5. In a tank construction an outer wall with an inner mastic seal, and an inner wall with an outer mastic seal, said seals separated by an open cellular construction, comprising

hollow tiles, said tiles forming channels to conduct away seepage coming through said inner wall, and openings through said outer wall at the bottom communicating with said channels.

6. In a pickling tank an outer wall with an inner mastic seal and an inner wall with an outer mastic seal, channeled members between said seals adapted to drain seepage coming through said inner wall, and openings in the floor which is adjacent said outer wall to emit said seepage.

7. In a pickling tank, an outer wall with an inner mastic seal and an inner wall with an outer mastic seal, channeled members between said seals adapted to drain seepage coming through said inner wall, and openings in the floor which is adjacent said outer wall to emit said seepage, a sub-floor beneath said floor to catch said seepage, and a gutter to conduct it away.

8. In a pickling tank an outer wall with an inner mastic seal, and an inner wall with an outer mastic seal, hollow tiles separating said seals, the vertical tiles laid with their cells vertically disposed, the horizontal tiles notched to permit liquid flow transversely of the cells, and openings through said outer wall forming drains.

30 9. In a pickling tank an outer wall with an inner mastic seal, and an inner wall with an outer mastic seal, hollow tiles separating said seals, the vertical tiles laid with their cells vertically disposed, the horizontal tiles notched to permit liquid flow transversely of the cells, and openings through said outer wall forming drains, said openings comprising vertical tiles in the floor which is adjacent said outer wall.

40 10. In a pickling tank a foundation comprising a sub-floor and supports for a tank, and a tank proper comprising outer walls and floor, said floor perforated by vertical hollow tiles forming communicating channels therethrough, a mastic seal over all inwardly exposed portions of said outer wall including the floor which is adjacent thereto, an inner wall and an outer mastic seal thereon, and a course of tiling interposed between said seals, said tiling providing channels for liquid flow, intercommunicating and communicating with said channels through said floor.

55 11. In a pickling tank, a foundation of concrete comprising a sub-floor and an acid-proof lining therefor and supports for a tank proper, and a tank proper resting upon said supports and comprising outer walls and floor of concrete, said floor pierced by transverse rows of hollow tiles forming channels therethrough, a mastic seal over all inwardly exposed portions of said outer wall including the floor which is adjacent thereto, a course of tiling covering said seal, said tiling providing channels for liquid flow, intercom-

municating and communicating with said channels through said floor, an inner mastic seal upon said course of tiling, and an inner acid-proof lining on said mastic seal.

12. In a pickling tank, a foundation of concrete comprising a sub-floor and an acid-proof lining therefor and supports for a tank proper, and a tank proper resting upon said supports and comprising outer walls and floor of concrete, said floor pierced by transverse rows of hollow tiles forming channels therethrough, a mastic seal over all inwardly exposed portions of said outer wall including the floor which is adjacent thereto, a course of tiling covering said seal, said tiling providing channels for liquid flow, intercommunicating and communicating with said channels through said floor, an inner mastic seal upon said course of tiling, and an inner acid-proof lining on said mastic seal, said sub-floor arranged to drain to a gutter, and a gutter to conduct away liquid flow.
